W. U. HARRIS.

CAN CLOSURE.

APPLICATION FILED MAR. 31, 1913.

1,084,857.

Patented Jan. 20, 1914.

UNITED STATES PATENT OFFICE.

WILLIAM USTICH HARRIS, OF MOBILE, ALABAMA.

CAN-CLOSURE.

1,084,857.

Specification of Letters Patent.

Patented Jan. 20, 1914.

Application filed March 31, 1913. Serial No. 758,018.

To all whom it may concern:

Be it known that I, WILLIAM U. HARRIS, a citizen of the United States, residing in Mobile, in the county of Mobile and State 5 of Alabama, have invented certain new and useful Improvements in Can-Closures, of which the following is a specification.

The object of this invention is to provide improved means for sealing and closing 10 cans, such as oil cans, and for conveniently opening and pouring from them when desired.

In carrying out my invention I provide means for sealing the cans airtight, a cover 15 or cap for closing the seal and an air tube for admitting air to the can when pouring. The air tube and pouring opening of the can are normally sealed, but the seal may be broken to admit air to the interior of the 20 can and provide a pouring orifice.

In the accompanying drawings I have shown several modified forms of my invention.

Figure 1 is a view partly in elevation and 25 partly in section illustrating an oil can with my invention applied. Fig. 2 is a detail plan view of a portion of the can showing the pouring orifice with the cap removed but with the seal unbroken. Fig. 3 is a sectional detail view of a part of the oil can shown in Fig. 1 with the cap lifted. Fig. 4 is a detail sectional view where the can has no spout or cap but where cutting and 30 punching orifices are indicated. Fig. 5 is a detail sectional view of another modification in which a portion of the can is depressed at the pouring part, a cutting part is indicated and the air tube is sealed by a 35 plug. Fig. 6 is a plan view of the modification shown in Fig. 5.

Referring first to Figs. 1, 2 and 3, A indicates a can of ordinary construction, it is provided with a threaded nozzle α which receives a screw cap B preferably carrying 45 a cork disk C. The outer end of the nozzle is sealed by metal at D. This metal is of such nature that it may be readily cut. The outer face of the sealing metal D is preferably scored at d and marked with the word 50 "cut". This sealing metal is also scored at d' and marked "punch".

Within the can is an air tube E which opens into the can at e and its outer end e' is arranged close to the punching portion d' 55 of the seal D. When the can is filled it is

tightly sealed at D and the cap B is applied. In this form the can is put on the market. The user can readily remove the cap B and then with a suitable tool cut the seal D at d and punch it at d' . The contents of the can 60 may then be easily poured. After the desired amount of material is poured from the can the nozzle may be closed by the cap B provided with the cork C. This affords a sufficient sealing means for the can until its 65 contents is exhausted.

In Fig. 4 the nozzle is dispensed with and a depression is formed at G in the can which is preferably scored at g to indicate where the can should be cut for pouring and it is 70 also scored at g' and marked "punch" to allow the air to enter the ventilating tube E.

In Fig. 5 a depression is formed in the can at H which depression is scored at h to indicate where the can is to be cut and the 75 air tube E extends into the flange h' of the depression. The plug I serves to seal the opening of the tube E. When the plug is removed air can freely enter through the tube and the can may be cut at h . The plug 80 is relied on to seal the openings when the can is in use.

Fig. 6 is a plan view of the can shown in Fig. 5 with the plug removed.

The can may be filled before sealing in 85 various ways. There may be an opening made anywhere in the can for filling purposes which may be tightly sealed, the pouring opening hereinbefore referred to being sealed in the manner before described, or 90 the can may be filled through the pouring opening and then this opening may be closed in various ways. Referring to Figs. 1, 2, 3, for instance, the spout may be formed integrally with the seal D and this spout may 95 be soldered at its lower or inner end to the can around the pouring opening, the seal D being formed integrally with the sides of the spout and the tube E is soldered to the seal D before the spout is soldered to the 100 can.

With reference to the construction shown in Fig. 4 the can there indicated may be filled through a specially provided filling opening and the seal G may be an integral 105 part of the top of the can, or an opening may be made in the can and the seal G may be made of a separate piece of metal and soldered to the can. As to the can shown in Figs. 5 and 6 the same is true. The can may 110

be filled through a specially provided opening which is properly sealed when the can is filled, or the part H may be made separately and soldered on to the top of the can. In each instance it will be observed that the top of the can has a portion off-set to form a pouring opening and said off-set portion is provided with a permanently attached seal.

I claim as my invention:

- 10 1. A can provided with a top having a portion offset to form a pouring opening which is provided with a permanently attached seal, an air tube opening into the can extending into the pouring opening and

being in contact with and closed by the metallic seal. 15

2. A can provided with a top having a pouring opening provided with a permanently attached metallic seal, an air tube opening into the can and having its outer end in contact with and closed by said metallic seal. 20

In testimony whereof, I have hereunto subscribed my name.

WILLIAM USTICH HARRIS.
